UNITED STATES PATENT OFFICE.

TIMOTHY F. McEVOY, OF POTTSTOWN, PENNSYLVANIA.

DERAIL.

1,079,990.

Specification of Letters Patent.

Patented Dec. 2, 1913.

Application filed January 21, 1913. Serial No. 743,233.

To all whom it may concern:

Be it known that I, TIMOTHY F. McEVOY, a citizen of the United States, residing at Pottstown, in the county of Montgomery and State of Pennsylvania, have invented certain new and useful Improvements in Derails, of which the following is a specification.

My invention relates to improvements in derails, the object of the invention being to so construct the movable derailing member that it will derail the cars moving in one direction only, and will be moved by the wheels of the car when the latter are moving in the opposite direction to permit the cars to pass without derailing.

A further object is to provide a device of this character in which the derailing member is elastically returned to derailing position after having been moved backwardly by the wheels of a car.

With these and other objects in view, the invention consists in certain novel features of construction and combinations and arrangements of parts as will be more fully hereinafter described and pointed out in the claims.

In the accompanying drawings: Figure 1 is a top plan view showing the device in operative position. Fig. 2 is a view in side elevation of Fig. 1. Fig. 3 is a view in longitudinal section on the line 3--3 of Fig. 1. Fig. 4 is a view in section similar to Fig. 3 but showing the movable member forced backwardly by a car wheel. Fig. 5 is a view in longitudinal section through the center of the stationary member, and Fig. 6 is a view in cross section on the line 6--6 of Fig. 3.

40 My improved device comprises in the main, two members 1 and 2, the former a stationary member and a guide for the latter, which is a movable member, and is the derailing member *per se*.

45 The stationary member 1 comprises a single casting having base flanges 3 adapted to be spiked to the ordinary ties, and these flanges 3 are made integral with vertical walls 4 and 5, the former connected by a transverse arched integral brace 6. While the walls 5 constitute rearward extensions of the walls 4, they are located closer together than are the walls 4, and constitute in effect, a restricted rearward extension on the main por-

tion of the stationary member and are connected at their rear ends by a transverse integral bar 7.

55 While I have illustrated a particular arrangement of strengthening webs on the base member, it is to be understood that a wide range of latitude is to be permitted in this regard, and the base member may be variously shaped to give to it the necessary strength and durability to withstand the strains to which it is necessarily subjected.

60 The forward end of the stationary member 1 extends upwardly in a plane higher than the main portion of the stationary member and bears directly against the web of the rail 8 as shown at 9 constituting a transverse platform which is provided with 70 two enlargements 10, and the inner faces of the walls 4 and 5 are provided with longitudinal grooves 11 and 12 for a purpose which will hereinafter appear.

75 The movable member 2 comprises a body portion 13 and a head or derail block 14 which is adapted to be moved onto and off the rail 8. The body 2, at one end, is of a width to fit between the walls 4, 4, but at 80 its rear end is restricted in width so as to fit between the walls 5, 5. The larger end and the smaller end of the body portion 2 are provided at opposite sides with lugs 15 and 16 respectively which move in grooves 12 85 and 11 respectively in the walls 4 and 5. These grooves 11 and 12 are so shaped that when the movable member 2 is moved longitudinally, they cause the member to move vertically so as to cause the head end of the 90 movable member to elevate and lift over the enlargements 10, and said movable member is recessed on its under face as shown at 18 to receive said enlargements 10 when the movable member is in active position, so 95 that the weight of a car wheel 19 on the head 14 serves only to press the movable member more tightly against the enlargement and precludes any possibility of rearward movement because vertical movement is prevented.

100 It will be noted that the walls of recesses 18 are curved and that the enlargements 10 are inclined or beveled, so that the movable member 2 may be moved rearwardly by the 105 wheel flange when no weight is upon the movable member. The weight of the car prevents any movement because the movable

member moves upwardly as well as longitudinally, but this action is readily carried out when the wheel flange engages the cam surface 22 hereinafter referred to.

- 5 The head 14 is formed with a beveled flange 20 extending from one end of the head to the center thereof to guide the wheel flanges to an inclined plane 20° on the head at the center of the head and direct said flanges over the rail, thereby derailing the same. The opposite end of the head inclines inwardly forming a tongue 21 which extends beyond the inner surface of the head of the rail, so that a wheel approaching the device 15 toward the tongue end of the head, will engage the beveled or cam face 22 of said tongue and force the movable member rearwardly without derailing as will be explained.
- 20 The movable member 2 is cast hollow with integral walls 23 and 24 at the opposite ends of said hollow cast portion. An operating rod 25 extends through both of these walls 23 and 24, and is screw-threaded so that it 25 receives at its forward end a nut 26 located against the front face of wall 23, so that when the rod is moved in one direction, it will draw the movable member from its active to its inactive position. A conical block 30 27 is located on the rod 25, is held against movement in one direction by lock nuts 28 on the rod, and at its larger end extends through an opening 29 in wall 24 and bears against one end of a coiled spring 30 located about the rod 25, and bearing at one 35 end against the wall 23. A block 31 is housed within the spring 30 on rod 25 and serves to hold the spring in its normal operative position.
- 40 It is to be understood that the rod 25 is to be connected with any suitable operating means so that the movable member may be moved manually from its active to its inactive position and vice versa, and when in 45 active position is elastically held against rearward movement.

It is, of course, to be understood that the weight of a car wheel on the head 14 absolutely prevents any rearward movement by 50 reason of the enlargements 10, but normally the spring 30 holds the movable member against rearward movement and returns said movable member to active position after a car wheel has passed in a direction which 55 will not derail.

The derail will be so placed upon a switch or turn-out that its tongue 21 will project toward the main track, so that if by accident the movable member is allowed to remain in 60 active position, it will not derail a train entering the switch or siding, but will derail a train on the switch or siding moving toward the main track.

It is to be understood that my derail is 65 intended to be operated manually to move

the movable member into active or inactive position, but in the event of an oversight, a train can enter the turnout without derailment, because each wheel of the train will, by reason of contact with the cam face 22, 70 move the movable member backwardly against the action of the spring 30, the former promptly returning the movable member to active position after the wheel is passed. 75

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letter Patent is:

1. A derail comprising a base and a movable derailing member, elastic means exerting a pressure on the derailing member to move the same toward the rail, means compelling the derailing member to elevate and then lower in its movement by the spring, means positively locking the derailing member against movement when a wheel is supported thereupon, and said derailing member having a cam face adapted to be engaged by a wheel flange to force the same away from the rail and against the action of the spring, substantially as described. 95

2. A derail comprising a base having 100 grooves adapted for supporting and guiding the derailing member toward and away from the rail, in combination with said derailing member having lugs movable in the grooves, said grooves curved upwardly 105 throughout a portion of their length, whereby the derailing member is caused to move upwardly and then downwardly into active position on the rail, means positively locking the derailing member against movement 110 when a wheel is supported thereupon, elastic means exerting pressure on the derailing member, holding the same in active position, a head on said derailing member having an inclined tongue at one end against which a 115 wheel flange is adapted to engage and move the member from active position, substantially as described.

3. A derail comprising a base having 120 grooves adapted for supporting and guiding the derailing member toward and away from the rail, in combination with said derailing member having lugs movable in the grooves, said grooves curved upwardly throughout 125 a portion of their length, whereby the derailing member is caused to move upwardly and then downwardly into active position on the rail, means positively locking the derailing member against movement when a wheel is supported thereupon elastic means 130

- exerting pressure on the derailing member, holding the same in active position, a head on said derailing member having an inclined tongue at one end against which a wheel flange is adapted to engage and move the member from active position, and a rod for positively moving said derailing member, said rod connected to said elastic means, substantially as described. 5
- 10 4. A derail comprising a stationary member, a movable member movable longitudinally in the stationary member, a derailing head on one end of said movable member, said head having an inclined tongue at one end, constituting a cam surface against which a wheel flange is adapted to engage and move the movable member toward its inactive position, guides in the stationary member guiding the longitudinal movement 15 of the movable member, said movable member having parallel walls spaced apart, an operating rod projecting through openings in both of said walls, a block adjustable on said rod and projecting through one of said walls, a nut on said rod in front of the other of said walls, and a coiled spring located between said last-mentioned wall and said block whereby said movable member is elastically connected to the rod, substantially as 20 described. 25
5. A derail comprising a stationary member, and a movable member guided in its movement by the stationary member, a derailing head on said movable member, an operating rod connected with the movable member, guiding means on the stationary member causing the elevation of the movable member during a portion of its longitudinal movement, enlargements on the stationary member over which the movable member engages when in active position, whereby a positive lock is formed for the derailing member when a wheel is supported thereupon, elastic means exerting pressure 30 on said movable member to hold the same in active position, said derailing head having an inclined tongue at one end against which a wheel flange is adapted to engage and move the movable member from active position, substantially as described. 35
- 40 6. A derail comprising a stationary member, and a movable member guided in its movement by the stationary member, a derailing head on said movable member, longitudinal grooves in the stationary member, lugs on the movable member guided in said grooves, said grooves curving upwardly throughout a portion of their length, whereby the movable member is caused to move upwardly and then downwardly during a portion of its longitudinal movement, enlargements on the stationary member over which the movable member engages when in active position, whereby a positive lock is formed for the derailing member when a wheel is supported thereupon, an operating rod movably connected to the movable member, elastic means connecting the rod to the movable member and exerting a constant pressure on the movable member to hold the latter in operative position, said derailing head having an inclined tongue at one end against which a wheel flange is adapted to engage and move the movable member from active position, substantially as described. 45 50
- 45 7. A derail comprising a stationary member, and a movable member guided in its movement by the stationary member, a derailing head on said movable member, longitudinal grooves in the stationary member, lugs on the movable member guided in said grooves, said grooves curving upwardly throughout a portion of their length, whereby the movable member is caused to move upwardly and then downwardly during a portion of its longitudinal movement, enlargements on the stationary member over which the movable member engages when in active position, whereby a positive lock is formed for the derailing member when a wheel is supported thereupon, elastic means exerting pressure on said movable member to hold the same in active position, said derailing head having an inclined tongue at one end against which a wheel flange is adapted to engage and move the movable member from active position, substantially as described. 55 60
- 50 8. A derail comprising a stationary member, and a movable member guided in its movement by the stationary member, a derailing head on said movable member, longitudinal grooves in the stationary member, lugs on the movable member guided in said grooves, said grooves curving upwardly throughout a portion of their length, whereby the movable member is caused to move upwardly and then downwardly during a portion of its longitudinal movement, enlargements on the stationary member over which the movable member engages when in active position, whereby a positive lock is formed for the derailing member when a wheel is supported thereupon, an operating rod movably connected to the movable member, elastic means connecting the rod to the movable member and exerting a constant pressure on the movable member to hold the latter in operative position, said derailing head having an inclined tongue at one end against which a wheel flange is adapted to engage and move the movable member from active position, substantially as described. 65 70
- 55 9. A derail comprising a stationary member, and a movable member guided in its movement by the stationary member, a derailing head on said movable member, guiding means on the stationary member guiding the movement of the movable member, said movable member having parallel walls spaced apart, an operating rod projecting through openings in both of said walls, a block adjustable on said rod, and projecting 75 80

through one of said walls, a nut on said rod in front of the other of said walls, and a coiled spring located between said last-mentioned wall and said block, whereby said 5 movable member is elastically connected to the rod, substantially as described.

In testimony whereof I have signed my

name to this specification in the presence of two subscribing witnesses.

TIMOTHY F. McEVOY.
